US00D947115S

(12) **United States Design Patent** (10) **Patent No.:** **US D947,115 S**
(45) **Date of Patent:** **** Mar. 29, 2022**

(54) **PORTABLE POWER SOURCE**

(71) Applicant: **GUANGDONG GOPOD GROUP HOLDING CO., LTD**, Shenzhen (CN)

(72) Inventor: **Zhuowen Liao**, Shenzhen (CN)

(73) Assignee: **Guangdong Gopod Group Holding Co., Ltd.**, Shenzhen (CN)

(**) Term: **15 Years**

(21) Appl. No.: **29/737,936**

(22) Filed: **Jun. 12, 2020**

(30) **Foreign Application Priority Data**

May 14, 2020 (CN) 202030219783.9

(51) **LOC (13) Cl.** **13-02**
(52) **U.S. Cl.**

USPC **D13/103**

(58) **Field of Classification Search**

USPC D13/102–106, 110, 118, 119, 184, 199
CPC Y02E 60/10; H01M 6/00; H01M 6/14;
H01M 6/05; H01M 6/10; H01M 6/52

(57) **CLAIM**

The ornamental design for a “portable power source”, as shown and described.

DESCRIPTION

FIG. 1 is a rear perspective view of a first embodiment of a portable power source showing the new design;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view of a second embodiment of a portable power source showing the new design;

FIG. 10 is a front perspective view of the second embodiment;

FIG. 11 is a front view of the second embodiment;

FIG. 12 is a rear view of the second embodiment;

FIG. 13 is a left side view of the second embodiment;

FIG. 14 is a right side view of the second embodiment;

FIG. 15 is a top view of the second embodiment; and,

FIG. 16 is a bottom view of the second embodiment.

The broken lines in the figures depict portions of the portable power source that form no part of the claimed design.

1 Claim, 16 Drawing Sheets
